(57) **CLAIM**

The ornamental design for a clamshell container as shown and described.

DESCRIPTION

FIG. 1 is a front and top perspective view of a clamshell container, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of the clamshell container in a closed position.

1 Claim, 8 Drawing Sheets
